UNITED STATES PATENT OFFICE.

ADOLPH VESTER, OF ATTLEBOROUGH, MASSACHUSETTS.

DESIGN FOR AN ORNAMENTAL PIN.

SPECIFICATION forming part of Design No. 11,735, dated April 13, 1880.

Application filed March 11, 1880. Term of patent 3½ years.

To all whom it may concern:

Be it known that I, ADOLPH VESTER, of Attleborough, in the county of Bristol and State of Massachusetts, have invented a new and 5 useful Design for Pins; and I do hereby declare that the following is a full, clear, and exact description of the same.

This design is intended more especially for application to shawl and other pins. It consists, essentially, of a bar having enlarged ornamental heads at each end, and of the representation of a bird perched upon such bar, such bird being shown as carrying in its bill a pearl or other gem. The bird is supported 15 by a wire wound spirally around the bar, which serves to give additional ornamentation to the device. Upon the bar is also placed the representation of an olive-branch or other foliage. The essential features of my design, however, 20 are the bar, to which is attached a fastening-pin, and the bird perched on such bar.

In the accompanying drawing, which shows

a general view of the entire device, A represents the bar; B B, the enlarged ornamental heads; C, the bird; D, the coiled wire, and E 25 the olive-branch attached to the bar.

The pin is intended to be made of gold or other metal, solid or plated, and forms a neat and attractive article of jewelry.

What I claim is—

1. The design for a pin herein described and shown, consisting of a bar and the representation of a bird perched thereon.

2. The design for a pin herein described and shown, consisting of a bar, a bird perched 35 thereon, represented as holding in its bill a pearl or other gem, and a branch with foliage.

In testimony whereof I have signed my name to this specification in the presence of two subscribing witnesses.

ADOLPH VESTER.
